UNITED STATES PATENT OFFICE.

LOUIS A. DOUILLET, OF NEW YORK, N. Y.

DESIGN FOR THE SURFACE ORNAMENTATION OF GLOVE-BUTTONS.

SPECIFICATION forming part of Design No. 19,176, dated June 25, 1889.

Application filed April 19, 1889. Serial No. 308,901. Term of patent 14 years.

To all whom it may concern:

Be it known that I, LOUIS A. DOUILLET, a citizen of the Republic of France, residing at New York, in the county and State of New York, have invented a Design for the Surface Ornamentation of Buttons to be Used for Gloves or Similar Articles, of which the following is a specification.

My design, which is illustrated in the accompanying drawing, has, first, a distinguishing background, which in the case of a metal button may be formed by roughening the metal, and in other buttons by any effect giving the same appearance. Upon this background is the distinguishing feature of my design, which is a series of bars radiating from a point eccentric to the center of the design. This principal feature of the design is inclosed by a circular boundary formed by a circular

band similar to the radiating bands, and the said radiating bands are connected at their inner end by a small circular band inclosing the center of radiation.

What I claim as new, and desire to secure by Letters Patent, is—

A design for the surface ornamentation of buttons, substantially as herein shown and described, having as its distinguishing feature a series of bars radiating from a point eccentric to the contour of the design, the said bars being provided with a circular boundary and connected at their inner ends by a curved bar inclosing the center of radiation.

LOUIS A. DOUILLET.
